UNITED STATES PATENT OFFICE.

JORDAN E. FOX, OF MEXIA, TEXAS, ASSIGNOR OF ONE-HALF TO WILLIAM REITER,
OF DALLAS, TEXAS.

ADJUSTABLE FISHING TOOL.

Application filed June 19, 1924. Serial No. 720,933.

To all whom it may concern:

Be it known that I, JORDAN E. FOX, a citizen of the United States, residing at Mexia, in the county of Limestone and State of 5 Texas, have invented certain new and useful Improvements in Adjustable Fishing Tools, of which the following is a specification.

This invention relates to fishing tools for oil or other wells, and refers more particularly to a device of this character which is simple of construction and which will securely engage the object to be lifted.

An object is to provide a device of this nature which will be easily adjusted for 15 operation and which is peculiarly formed to slip over the object to be lifted and guide same into contact with the gripping members of the device.

A still further object is to provide a device which will have the weight of the object lifted, distributed or directed into the body of the device in a direction longitudinal with the walls of the device, thus avoiding excessive lateral pressure.

25 A feature of the invention, it will be observed, is the fact that the tool is so constructed that there are no projections on the outer periphery that might interfere with or hinder the progress of the tool up and down the casing.

30 Another feature is the adjusting principles of the gripping means.

Other objects and features, as well as those hereinbefore mentioned, may be more 35 readily understood by following the description herewith, of which the annexed drawings form a part, and in which:

Figure 1 represents a side elevational view of the invention.

40 Figure 2 shows a sectional side elevation of the invention with the body extension member.

Figure 3 is a cross section of Figure 1.

45 Figure 4 is a cross section of Figure 1 at points 4—4.

Following the figures: 1 denotes the upper portion of the cylindrical body of the device which is adapted to be secured by threads to the lower body portion 2. In this latter body portion, four cuts 9—9 are made 50 of equal size and shape, and at the upper central portion of these cuts are situated springs 4, fastened at points a—a. These springs apply against jaws 3—3 which are

journaled on pins 5—5 in the body 2. The butts of these jaws are rounded at points 3—a in conformable fitting to seats in the body wall so that pressure on the jaws applies against the body in a downward direction and that pressure is not exerted on the pins 60 themselves. These jaws have teeth B on the upper edges thereof.

It will be observed by reference to the drawings that the tool is provided in its upper element with a series of apertures 1—a in order that the liquid may be provided with an outlet when the device is being lowered into the casing. In the lower portion of the body, an inner flare 6 is made which enables the tool to receive more effectually 70 the object to be lifted.

At the top of the member 1 a shoulder 7 is formed on the stem 8, which has a square shoulder 7—a to allow the purchase of a wrench for screwing the member 1 down on 75 the member 2, or upon the extension 6. In the latter case the extension is screwed upon the member 2.

In operation, the tool is assembled and lowered in the well over the object to be 80 raised. The jaws grasp this object as soon as the device is lowered over it, as the springs bring them into engagement with the object, grasping it on all sides and the tool is lifted from the well with the object 85 within it.

It should be understood that the extension is used when it is desired to grasp a longer object.

It will also be observed, by reference to 90 Figure 1 of the drawings that the device has an elongated stem upon the upper portion thereof and which is adapted to be used in fishing for the tool itself in event it is broken off in the well.

It should also be understood that various minor changes may be made in the construction and arrangement of the invention without departing from the spirit and intent of the following claims:

1. A fishing tool including an elongated tubular body having diametrically opposed slotted apertures in the walls thereof; paired spring controlled toothed gripping jaws mounted in the slots of each of said apertures, one pair disposed above the other at right angles thereto; shoulders on said jaws, and projections on the inner periphery of 105

said tubular body to engage the shoulders of said jaws on the downward movement thereof.

2. A fishing tool including a hollow cylindrical body in sections; a pair of diametrically opposed gripping jaws pivoted in the walls of the lower body section; a second pair of diametrically opposed gripping jaws disposed below the first named

jaws at right angles thereto; lateral shoulders on each of said gripping jaws; projections on the inner periphery of said lower body section engageable by the shoulders of said gripping jaws, and means for normally holding said jaws in such engagement. 10 15

In testimony whereof I have signed my name to this specification.

JORDAN E. FOX.
